JET MILLS AND THE LIKE

Helmut Vogel and Martin Hartmann, Wolfenbuttel, and Herbert Spitzner, Berlin-Wilmersdorf, Germany, assignors to Schering A.G., Berlin, Germany, a corporation of Germany

Filed Feb. 16, 1960, Ser. No. 8,954

Claims priority, application Germany Feb. 24, 1959

8 Claims. (Cl. 241—39)

This invention relates to jet mills, and the like. Jet mills for the very fine grinding of solids are already known. They operate in accordance with the principle of the impact mill, the acceleration of the material to be ground being effected not by mechanically moved parts of the apparatus, but rather by the energy of gas or vapor jets which expand into the grinding chamber. They can, for instance, be constructed in a manner that a round or disc-shaped grinding chamber is provided on its top with a tangentially directed injector nozzle for the introduction of the material to be ground; or on its periphery with a large number of inlet nozzles for the propellant gas, which nozzles are directed tangentially thereto in the same direction, and in the center with an outlet opening for the discharge of the ground material and the expanded propellant gas.

In commercial types of jet mills, the diameter of the grinding chamber can be about 50 to 1200 mm. and its height about 25 to 62 mm. There are used about 3 to 16 propellant nozzles, the outlet openings of which may have a diameter of 1.4 to 6 mm. As propellants, air, superheated steam or other gases of a pressure of about 3 to 10 atmospheres gauge are used. The ground material is separated in a subsequent cyclone with or without a filter.

Such jet mills are used particularly for very finely comminuting substances which are sensitive to heat and chemicals and in which high requirements as to fineness and uniformity of the grain as well as purity are necessary.

In operating such mills in actual practice, it has however, been found that many substances which absolutely require such a gentle grinding, for instance plant protective agents, pharmaceutical substances, etc., cannot be dependably comminuted with a satisfactory quantitative output. A crust is formed, predominantly in the outer zones of the grinding chamber, so that the feeding of the propellant and the removal of the fine dust become irregular and pieces of crust which have broken off are contained in the final product. This situation can sometimes be improved by strongly reducing the feed of the material to be ground while keeping the amount of propellant unchanged, by frequently opening and cleaning the grinding chamber and by drying the propellant before its introduction into the grinding chamber, which, however, impairs the economy of the grinding process.

It is an object of the present invention to overcome the above noted disadvantages.

Another object of the present invention is to provide a jet mill in which the lateral wall of the grinding space thereof is developed in a stepwise manner.

Another object of the present invention is to provide a mill having at the top of the grinding chamber, a device which makes possible a variable adjustment of the injector nozzle in such a manner that the horizontal angle between the axis of the nozzle and the radius of the grinding chamber is variable.

Still another object of the present invention is to provide a mill having a valve or a similar device which is so developed that it makes possible the closing of the discharge opening for the ground material and propellant one or more other openings which open into the grinding chamber being simultaneously exposed.

2

Other objects will become apparent from the following detailed description taken in conjunction with the accompanying drawing, in which:

FIGS. 1 and 2 show schematically, by way of example, of a preferred embodiment sections through the mill obtained when employing the inventive concept.

A grinding chamber A, FIG. 1, has an outer circular periphery and the interior has, for instance, three recessed portions forming circular steps, 10, 11 and 12 respectively.

10 A central outlet pipe B extends from the bottom of chamber A for the mixture of propellant of ground material, while a feed opening C for the material to be ground is mounted on eccentric disc H₁. The propellant, which at the same time serves to feed the injector nozzle, 15 D disposed at the opening C, enters the mill at areas E, F and G and after emerging from the tangential nozzles or boreholes d, e, f, and g, expands down to a pressure slightly above atmospheric pressure.

On the top of the grinding chamber, there are provided, 20 two eccentric discs H₁ and H₂; FIGS. 1 and 2, by means of which a change of the angle α , FIG. 2 between the axis of the injector nozzle and the chamber radius is possible. By turning disc H₁ through angle α_1 , the axis of the injector nozzle can be brought from the direction R₁ into 25 the direction R₂, while by turning the disc H₂ through an angle of 90° it can be brought from R₂ into the direction R₃. Upon the turning from R₂ towards R₃, the length of the path of the jet until it impinges upon the wall of the grinding chamber is also changed, which is of great 30 importance in order to prevent the formation of a crust during the pulverizing operation.

Although the formation of a crust is very substantially prevented by the development, in accordance with the invention, of the cross-section of the grinding chamber and 35 the possibility of varying the angle at which the material to be ground is charged, it is nevertheless possible, in the case of substances which are very difficult to grind or which tend readily to bake-on, that crusts will form after longer periods of operation. These crusts can be removed

40 without the cumbersome removal of entire parts of the apparatus being necessary as was formerly the case. It is merely necessary to lower the valve plate K which is mounted on an outwardly open tubular guide member M guided in a stuffing box J, FIG. 1, and formed with openings L axially spaced from the valve plate K. In this manner, the connection cap B is tightly closed and the openings L in the tubular guide member M are exposed. Flushing or drying of the grinding chamber can now 45 be effected with any desired liquids, vapors or gases which are fed for instance to the connections D, E, F and G and discharge at L, whereupon the grinding can be continued after restoration of the grinding condition of the 50 grinding chamber.

The preferred embodiment described above of the improvements in accordance with the invention constitute 55 merely one example. There are many possibilities of structural variation which fall within the scope of the invention and which are to be employed in the specific case. Thus the grinding chamber may have merely two or more than three steps and the inlet nozzles can be present on 60 all or only a few of the steps.

Excellent advantages of the invention have been shown by the effectiveness of the measure and proven by numerous tests on a grinding chamber, the outer wall of 65 which had three steps of a diameter of 550 mm., 450 mm. and 350 mm. respectively, each of a height of 20 mm. and which was provided with a total of 54 tangential propellant nozzles in which compressed air of an initial pressure of 7 atmospheres gauge was expanded. As material to be ground, there were employed various substances 70 which had always given difficulties in other devices due to the formation of a crust and the breaking off of crusts

when ground in the previously known jet mills of the "micronizer" type. In each case, it was found that the new type of mill could be operated five to ten times longer before the formation of crusts led to difficulties in operation. Also the possibility of adjusting the angle of the feed nozzle to the optimum value had a favorable influence on the reduction of the formation of crust and on the uniformity of the particle size of the final product. Furthermore, the elimination of crusts was easily possible by using the flushing device. Also the consumption of compressed air per kg. of material ground is not higher, and that the capacity of the mill for the same diameter grinding chamber was about 20 percent greater.

While a preferred form of the invention has been described and illustrated, it is to be understood that changes or modifications as to form, arrangement of parts and use of materials may be made without departing from the spirit and scope of the invention as claimed.

We claim:

1. A jet mill for finely grinding solids, comprising a cylindrical chamber, which is provided with tangentially directed inlet nozzles for propellant gas, said nozzles being arranged on the periphery of the chamber, an injector nozzle directed tangentially in the same direction as the nozzles for the introduction of the material to be ground, said chamber having a central outlet opening for the discharge of the ground material and of the expanded propellant gas, said chamber having a pair of eccentrically mounted covers for variable adjustment of the injector nozzle whereby the horizontal angle α between the nozzle axis and the radius of the grinding chamber is adjustable.

2. A jet mill for the grinding of solids, comprising a chamber having an axis and provided on the periphery with tangentially directed inlet nozzles for propellant gas; an injector nozzle on the top of the chamber directed tangentially in the same direction as the inlet nozzles for the introduction of the material to be ground, said chamber having a central outlet opening for the discharge of the ground material and of the expanded propellant gas; and closure means for closing the outlet opening for ground material and propellant, at least one opening in said closure means communicating with the grinding chamber being simultaneously exposed when said outlet opening is being closed.

3. A jet mill according to claim 2, said chamber having an axially extending stepped wall, and said inlet nozzles for propellant gas being mounted on said wall of said chamber.

5. A jet mill for grinding solids comprising a chamber having an axis, an axially extending side wall, and a top wall transverse of said axis, said side wall having a substantially circular cross section decreasing stepwise in an axial direction away from said top wall; a plurality of tangentially disposed inlet nozzles in said chamber; injector nozzle means mounted on said top wall for injecting a material to be ground into said chamber in a tangential direction relative to said axis; and a discharge conduit axially communicating with said chamber.

10 15 6. A jet mill as set forth in claim 4, wherein said inlet nozzles are disposed tangentially in said tangential direction relative to said axis.

20 25 7. A jet mill as set forth in claim 4, further comprising a tubular guide member; valve plate means mounted on said tubular member, said member being and formed with an opening spaced from said valve plate means and slidably movable into and out of said chamber toward and away from a position in which said valve plate means closes said discharge conduit, and said opening communicates with the interior of said chamber.

30 35 8. A jet mill as set forth in claim 4, wherein said side wall has a plurality of alternating radially and axially extending annular portions, two adjacent ones of portions jointly constituting a step in said side wall respective ones of said inlet nozzles being mounted on a plurality of said steps.

9. A jet mill as set forth in claim 4, further comprising pivot means on said top wall, said injector nozzle means being mounted on said pivot means for pivoting movement about an axis extending in the direction of the axis of said chamber.
